5 Claims. (Cl. 42—1)

This invention relates to a method of and means for throwing grenades by means of firearms.

Modern firearms, and more especially semi-automatic or automatic rifles are generally provided with a muzzle brake or flame-concealer comprising a number of vents at the end of the barrel of the weapon. These vents have the disadvantage of obstructing the throwing of anti-tank, anti-personnel, smoke and other grenades by means of the conventional arrangement, such as the discharger cup fixed at the end of the barrel of the weapon. In fact, the presence of the said vents entails a substantial reduction of the pressure exerted on the end of the tail of the grenade owing to the lateral escape of a part of the gases through the said vents and, in consequence, a detrimental loss of velocity.

Attempts have been made to solve this problem by increasing the dimensions of the muzzle brake, for example, so as to adapt its outside diameter to the inside diameter of the tail of the grenade. This solution has the disadvantage already cited above, namely, a substantial loss of the pressure of the gases and, in consequence, of initial velocity, owing to the exposure of the vents as the grenade moves forward and, moreover, this modification entails an increase in weight at the end of the weapon, which may influence the firing conditions.

Furthermore, with the discharger cups of the usual type, which are fixed on the weapon permanently during grenade firing, only grenades adapted to the discharger cup in question can be used, and the discharger cup is fitted with a sight corresponding to these grenades. This arrangement renders it impossible to use other grenades adapted to produce different effects, for example incendiary grenades, smoke, anti-personnel and other grenades. In addition, it is found that the precision obtained when firing bullets with a weapon provided with such a sleeve is considerably less than when firing is carried out without a discharger cup.

There are also weapons containing no muzzle brake or like device and the barrel of which, at its end, has no member adapted to cooperate in the fixing of a discharger cup of the usual type, for example a front sight.

The sleeve of the present invention is equally well suited for throwing grenades by means of such weapons. It may be fitted to all the types of such weapons hereinbefore described, without entailing modification of their barrels, and it enables the aforementioned drawbacks to be obviated.

The sleeve according to the invention is characterised in that it comprises means which, on the one hand, enable it to be maintained on the barrel of the weapon in such manner that it can be detached therefrom when the shot has been fired so that when throwing occurs it is projected forward after the grenade, and, on the other hand, enable the displacement of the sleeve on its support to be effected at a very reduced speed in relation to that of the grenade.

When the sleeve of the present invention is intended for throwing grenades by means of firearms in which the barrel is provided with a muzzle brake or a similar device, it constitutes at one and the same time a discharger cup on which the tail of the grenade is fitted and an obturator intended to mask at least partially the

2

vents of the said muzzle brake, the velocity communicated to it, which is very low in relation to that of the grenade, enabling it to mask the said vents for at least the greater part of the propulsion path of the said grenade.

The invention also relates to a method of throwing grenades by means of the hereinbefore described sleeve, which is characterised in that a sleeve is disposed inside the tail of each grenade and the assembly formed by the latter and the said sleeve is fitted on the barrel of the weapon.

In order to enable the invention to be more readily understood, reference is made to the accompanying drawings which illustrate diagrammatically and by way of example, three embodiments thereof, and in which:

FIGURE 1 is a longitudinal section of the sleeve supporting a grenade and fitted on the barrel of a firearm provided with a muzzle brake;

FIGURE 2 is a similar view of the sleeve of FIGURE 1, but in a different position in relation to the barrel of the weapon;

FIGURE 3 shows a modification of the sleeve; and

FIGURE 4 shows another modification of the sleeve.

FIGURE 1 shows the end of the barrel 1 of an automatic rifle, which barrel is provided with a muzzle brake comprising a series of vents 2. The throwing of anti-tank, anti-personnel, smoke, and other rifle grenades by means of such a weapon is effected by means of a tubular sleeve 3 which is retained inside the tail of each grenade and which is intended to be fitted with slight friction on the barrel 1 so as to mask the said vents 2. The inner wall of the sleeve 3 has a collar 4 adapted to abut against the end of the barrel 1 for the purpose of locating the sleeve on its support. The sleeve 3 also has a retaining device constituted by an elastic metal ring 5 housed in a groove 6 in the inner wall of the sleeve, said ring being adapted to exert on the periphery of the barrel 1 a clamping force sufficient to ensure that the sleeve is held in all the circumstances imposed by firing in the field, especially firing when the nozzle of the barrel is pointed downwardly. A similar retaining device, constituted by an elastic metal ring 7 housed in a groove 8, is disposed at the periphery of the sleeve 3 for the purpose of holding it inside the tail 9 of the grenade.

At the time of firing, the assembly constituted by the grenade and the sleeve 3, which is already in place inside the tail 9, is fitted on the barrel 1 (FIGURE 1). When the shot leaves, the major part of the propulsion gases issuing from the cartridge, bearing on the end of the tail 9 of the grenade, causes the latter to be projected forwardly. A small part of the gases, however, bearing on the rear face of the collar 4 of the sleeve 3, tend to project the sleeve 3 forward as well, the speed driving the latter being however extremely reduced in relation to that imparted to the grenade. The low velocity imparted to the sleeve 3, which will fall a few yards from the rifleman, enables the vents 2 to be closed during the greater part at least of the path of the grenade on the said sleeve (FIGURE 2).

FIGURE 3 shows a modification of the sleeve of FIGURES 1 and 2, in which a collar 4a, constituted by a separate metallic ring, is secured to the sleeve 3 by crimping.

The modification illustrated in FIGURE 4 relates to the device retaining the sleeve on the barrel of the weapon. This device consists of a clamp 10 comprising on the one hand a series of elastic strips 10a held in a housing 11 provided in the inner wall of the sleeve for the purpose of securing said clamp to the latter, and on the other hand a series of elastic strips 10b adapted to exert a retaining force on the barrel of the weapon.

It is obvious that the sleeve of the present invention can be applied equally well to the throwing of grenades

by means of rifles and by means of pistols or other weapons of the same kind.

What I claim is:

1. In combination with a rifle having a vented muzzle brake and a rifle grenade having a hollow tail section adapted to be mounted on the barrel of said rifle, a readily slidable launching sleeve slidably mounted within said tail section and slidably surrounding the muzzle of the rifle, and means to move the sleeve forwardly from the barrel, with the grenade, comprising an apertured member projecting inwardly from the sleeve in front of the rifle barrel and in the path of the gases from the barrel.

2. In combination with a rifle having a vented muzzle brake and a rifle grenade having a hollow tail section adapted to be mounted over the barrel of said rifle, a readily slidable launching sleeve slidably mounted within said tail section and slidably surrounding the muzzle of the rifle, and means to move the sleeve forwardly from the barrel with the grenade, comprising an annular collar projecting inwardly from the sleeve in front of the rifle barrel and in the path of the gases from the barrel.

3. A launching device as defined in claim 2 in which the collar is integral with the sleeve.

4. In combination with a rifle having a vented muzzle brake and a rifle grenade having a hollow tail section

adapted to be mounted over the barrel of said rifle, a readily slidable launching sleeve slidably mounted within the tail section and slidably surrounding the muzzle of the rifle, and means to move the sleeve forwardly from the barrel with the grenade, comprising an annular collar projecting inwardly from an intermediate part of the sleeve in front of the rifle barrel and in the path of the gases from the barrel.

5. In combination with a rifle having a vented muzzle brake and a rifle grenade having a hollow tail section adapted to be mounted over the barrel of said rifle, a readily slidable launching sleeve slidably mounted within the tail section and slidably surrounding the muzzle of the rifle, an annular collar projecting inwardly from an intermediate part of the sleeve in front of the rifle barrel and in the path of the gases from the barrel and friction means between the sleeve and both the rifle muzzle and the tail section to effect initial relative movement of the sleeve away from both the barrel and the tail section.
